UNITED STATES PATENT OFFICE

125,025

DESIGN FOR A MIRROR OR SIMILAR
ARTICLE

Harry Levine, New York, N. Y.

Application December 1, 1939, Serial No. 88,602

Term of patent 14 years

To all whom it may concern:

Be it known that I, Harry Levine, a citizen of the United States, residing at No. 877 Macy Place, in the county of Bronx and State of New York, have invented a new, original, and ornamental Design for a Mirror or Similar Article, of which the following is a specification, reference being had to the accompanying drawing, forming part thereof.

In the drawing

Fig. 1 is a front view of a mirror, showing my new design;

Fig. 2 is a sectional view of a broken-away part of said mirror; said view being taken along the section line 2—2 in Fig. 1, looking in the direction of the arrows; and

Fig. 3 is a front view of another broken-away part of the mirror shown in Fig. 1.

The characteristic feature of my design resides in the border composed of silvered and unsilvered portions the outermost one of which is unsilvered, a typical section thereof being shown in Fig. 3. The outline of the mirror, or similar article, is unimportant to such characteristic feature.

I claim:

The ornamental design for a mirror or similar article, substantially as shown and described.

HARRY LEVINE.
